CLAIM

The ornamental design for a physiological monitor receptacle, as shown and described.

DESCRIPTION

FIG. 1 is a front perspective view of a design for a physiological monitor receptacle;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a rear perspective view thereof showing a movable flap in a first open position to demonstrate movement of the movable flap;

FIG. 9 is a rear perspective view thereof showing a movable flap in a second open position to demonstrate movement of the movable flap;

FIG. 10 is a rear perspective view thereof engaged with unclaimed apparel; and,

FIG. 11 is a front perspective view thereof engaged with unclaimed apparel.

The broken lines showing the apparel in FIGS. 10 and 11 represent environmental subject matter and form no part of the claimed design; the remaining broken lines depict portions of the physiological monitor receptacle that form no part of the claimed design.
